UNITED STATES PATENT OFFICE.

THOMAS R. HARPER, OF PHILADELPHIA, PENNSYLVANIA.

DESIGN FOR A FLASK.

No. 38,970.

Specification for Design.

Patented Dec. 31, 1907.

Application filed June 17, 1907. Serial No. 379,521. Term of patent 3½ years.

To all whom it may concern:

Be it known that I, THOMAS R. HARPER, a citizen of the United States, residing at the city of Philadelphia, in the county of Philadelphia and State of Pennsylvania, have invented a new, original, and ornamental Design for Flasks, of which the following is a specification, reference being had to the accompanying drawing, forming part thereof.

The figure is a perspective view of a flask, showing my new design.

I claim:

The ornamental design for a flask, as shown.

THOMAS R. HARPER.
